UNITED STATES PATENT OFFICE.

BENJAMIN A. TOEDTER, OF PUEBLO, COLORADO.

HUMIDIFIER FOR GASOLENE-ENGINES.

1,231,312.

Specification of Letters Patent. Patented June 26, 1917.

Application filed September 2, 1916. Serial No. 118,298.

To all whom it may concern:

Be it known that I, BENJAMIN A. TOEDTER, a citizen of the United States, and a resident of Pueblo, in the county of Pueblo 5 and State of Colorado, have invented a certain new and useful Improvement in Humidifiers for Gasolene-Engines, of which the following is a full, clear, and exact description.

10 My invention is an improvement in means for supplying water vapor to the explosive mixture of gasolene engines and is particularly adapted for use in connection with automobile engines. The objects of my invention are: first, to provide means for supplying water vapor to the mixture just subsequent to carburization; second, to provide automatic means for admitting this water vapor in predetermined quantities; third, to 15 provide means for adjusting the same humidifier to operate in connection with engines of various sizes; fourth, to provide means for circulating the water from the water cooling system of the engine through 20 the device for generating the vapor to be used; and, fifth, to provide such a device that when adjusted to any particular gasolene engine it will operate automatically for that engine without further adjustment. 25 In the single view of the drawings accompanying this application I have illustrated my device as applied to an automobile engine, my device being shown in the central vertical section and the automobile and its carburetor in broken sectional elevation. 30

Referring to the drawings, my device comprises an outer reservoir A through which the water of the cooling system circulates and an inner evaporating reservoir or chamber B which is in communication with the carburetor of the engine. As shown in the drawings, the reference numeral 1 indicates the wall of the outer reservoir and 2 the wall of the inner one. Water is admitted to reservoir A through the pipe 3 which is in communication with the lower water pipe 4 of the engine cooling system. Water entering through 3 passes through the reservoir A and escapes through the pipe 5 into the high 45 or return pipe 6 of the cooling system.

The inner reservoir B has a port at its lowest point communicating with the reservoir A, this port being controlled by a cone valve 7 operated by the float 8 within the

reservoir B. The stem of the valve 7 is continued axially above the float 8 as shown at 9 and passes out through the neck 10 which projects above the cover plate 17. A screw cap 11 closes the neck 10 and surrounds the enlarged head 12 of the stem 9, this head 12 being of such size as not to be able to pass through the neck 10.

In the top of the reservoir B there is provided a port 14 adapted to be controlled by a manually operated pin-valve 13. The port 14 is in communication with a pipe 15 which leads, as shown, into the top of the carburetor 16. I prefer to make the reservoirs A and B cylindrical in form with outwardly turned top flanges 18 and 19 and to support both these reservoirs by connecting them to the top plate 17 by means of bolts as shown, the top plate 17 being supported by any suitable part of the engine structure. The parts should be so made that the joint between the flange 19 and the top 75 plate 17 is air-tight; consequently any suction set up through the port 17 will tend to produce a vacuum in B.

Operation.

80

The heated water circulating through 3, A, and 5 will tend to vaporize the water in B, this tendency being increased by the diminished atmospheric pressure in B. The suction set up by the engine through the intake will draw any vapor so produced into the top of the carburetor through the pipe 15. The amount of vapor drawn off from B can be conveniently regulated by manipulating the valve 13 and when this is once set for a given engine substantially a uniform amount of vapor will be discharged inasmuch as the vaporization takes place in a secondary chamber, heated by the water system, the temperature of which does not materially vary.

When the level of the water in reservoir B has fallen to such a point that the water will not keep the float 8 in suspension the valve 7 opens and more water is admitted until the float rises to such a point as to close the valve 7 again.

If it should be desired to drain the water from the cooling system to replace the same or to prevent freezing, the cap 11 is unscrewed and the float 8 is depressed by pressure on the head 12 thus opening the

valve 7. The head 12 is larger than the neck 10 so as to prevent the float 8 from falling so low as to close the intake to B and thus prevent water entering B when 5 the system is again filled.

While I have described my device as a separate entity and therefore requiring the provision of a reservoir A it will be obvious that this reservoir may be constituted by a 10 pocket cast, or otherwise formed, on the water jacket of the engine at any convenient point; or that a portion of the radiator properly made may form this outer heating chamber.

15 Having thus described my invention, what I claim and desire to secure by Letters Patent is:

1. In combination with a water-cooled gas engine, a vaporizing reservoir, connections from said reservoir to the intake of said engine, and means for circulating the cooling water of said engine around said vaporizing reservoir.

2. In combination with a water-cooled 25 gas engine, an air-tight vaporizing reservoir, connections from said reservoir to the intake of said engine, and means for circulating the cooling water of said engine around said vaporizing reservoir.

3. In combination with a water-cooled gas engine, a vaporizing reservoir having a feed port in its bottom and a vapor outlet port in its top, a float operated valve controlling said feed port, connections from 35 said vapor outlet port to the intake of said engine, and means for circulating the cooling water of said engine around said vaporizing reservoir.

4. In combination with a water-cooled 40 gas engine, a vaporizing reservoir having a feed port in its bottom and a vapor outlet port in its top, a float operated valve controlling said feed port, a manually operated valve controlling said vapor outlet 45 port, connections from said vapor outlet

port to the intake of said engine, and means for circulating the cooling water of said engine around said vaporizing reservoir.

5. In combination with a water-cooled gas engine, an outer reservoir, means for circulating the cooling water of said engine through said reservoir, an inner vaporizing reservoir, a float controlled valve in the bottom of said vaporizing reservoir affording communication between said reservoirs 55 and adapted to maintain said vaporizing reservoir partially filled with water from said outer reservoir, and connections from said vaporizing reservoir to the intake of said engine.

6. In combination with a water-cooled gas engine, an outer reservoir, means for circulating the cooling water of said engine through said reservoir, an inner vaporizing reservoir, a float controlled valve in the bottom of said vaporizing reservoir affording communication between said reservoirs 65 and adapted to maintain said vaporizing reservoir partially filled with water from said outer reservoir, a vapor outlet port in the top of said vaporizing reservoir, a manually operated valve for said outlet port, and connections from said outlet port to the intake of said engine.

7. In combination with a water-cooled 75 gas engine, a vaporizing reservoir having a feed port in its bottom and an open topped neck in its top in line with said port, a valve controlling said feed port, a stem on said valve projecting through said neck, a float on said stem within said vaporizing reservoir, a head on said stem larger than said neck, a cap for sealing said neck, connections from said reservoir to the intake of said engine, and means for circulating the 85 cooling water of said engine around said vaporizing reservoir.

In testimony whereof I have hereunto affixed my signature.

BENJAMIN A. TOEDTER.
